UNITED STATES PATENT OFFICE.

CARL J. FAULKNER, OF DAYTON, OHIO.

DISPLAY RACK.

Application filed March 2, 1921. Serial No. 449,182.

To all whom it may concern:

Be it known that I, CARL J. FAULKNER, a citizen of the United States, residing at Dayton, in the county of Montgomery and 5 State of Ohio, have invented certain new and useful Improvements in Display Racks or the like, of which the following is a specification, reference being had therein to the accompanying drawings.

- 10 This invention relates to improvements in display racks, having particular reference to racks provided with suitable bins for receiving and displaying fruit and vegetables, or the like.
- 15 An object of the invention is to provide a display rack which will be readily accessible for supplying the bins thereof with the fruit or vegetables to be displayed, and for retailing the same therefrom, which will be of 20 substantial construction, compact as to space required for display purposes; which will be sanitary, readily movable from one place to another, and which will be of attractive appearance and in all respects suitable for 25 displaying with good effect the produce in its bins.

An object of the invention is to provide suitable racks and bins for fruit or vegetables in bulk, and other racks for produce 30 in baskets or boxes, and still other racks for displaying certain fruit, as bananas, in bunches.

As illustrated in a preferred design and construction, in the accompanying drawings;

Fig. 1 is a side elevation of my improved rack;

Fig. 2 is an end elevation of the same;

40 Figs. 3 and 4 are detail views illustrating the construction of the basket rack, and

Fig. 5 is a detail view of a basket or box rack of modified construction.

As shown in the drawings, the frame structure consists of opposite base castings 45 1, spaced apart and joined one to the other by a base tie rod 2, the bases 1 being provided with castors 3; posts 4 extending upwardly from bases 1 and having secured to their upper ends by means of couplings 5

50 posts 6 of larger diameter, the upper extensions of posts 6 consisting of posts 7 joined one to the other by a connecting bar 7^a and having horizontal bars 8 terminating in opposite hooks 9, the posts 4, 6 and 7 being 65 made preferably of piping to obtain lightness of construction. Posts 6, as here shown,

have holes drilled through them as indicated at 10 to receive transverse bars 11 disposed horizontally therein, and flattened at their ends and drilled to receive bolts 12 for securing the racks 13—14—15 to the bars.

The rack may be of any suitable construction and arranged in any desired relation one to another. As here shown, the racks are disposed horizontally one above 65 the other in a vertical plane, the lowermost rack 13 being substantially longer and wider than rack 14 above it, and rack 14 longer and wider than rack 15, thus effecting a well-balanced structure, of attractive design 70 and providing for convenient access to the rack bins.

The rack construction consists of a closed bottom made, preferably, of sheet metal, the vertical sides 16 and ends 17 being constructed of close-mesh wire netting, reinforced at the upper and lower edges along the sides and ends by strips of metal 18—19 and 20—21, the corners being strengthened and finished with metal reinforcements 22. 80

Each of the racks 13, 14 and 15 is divided into a plurality of side bins 30 and end bins 31 by means of adjustable transverse partitions 23 and racks 13 and 14 with fixed longitudinal center partitions 24, the transverse 85 partitions being pivoted as at 25 to provide for adjusting the partitions rotatably to open the racks full length for removing from the bins any refuse remaining therein after the same have been used. 90

The longitudinal partitions 24 are substantially higher than the sides of the bin and the transverse partitions 23 increase in height from their outer ends inwardly to increase the capacity of the bins and to add 95 attractiveness of design to the display device as a whole.

Mounted on the posts 4, between bases 1 and lower rack 13, are rotatable brackets 26 each supporting a plurality, four as here 100 shown, of detachable individual basket racks 27 which are adapted to support at a convenient angle bushel baskets of standard size, the rack as a whole being mounted to rotate around post 4 to provide for convenient placing of baskets thereon and for ready accessibility to all of the baskets to retail fruit or vegetables therefrom.

The racks 27 are made detachable, as illustrated in Fig. 3, to provide for interchangeability of racks suitable for supporting baskets and boxes of different kinds and sizes,

a rack of modified construction being illustrated in Fig. 5, in which rack bars 32 are interchangeable with bars 26^a in the supporting bracket or housing 26 for the basket brackets 27, a plurality of trays 33, suitable for receiving fruit or vegetables in bulk or smaller trays, being supported on bars 32 in any suitable manner.

For ease of operation brackets 26 are provided preferably with roller bearings, as illustrated at 28 and 29 in Figs. 3 and 4, the bearings illustrated being of special design to suit the requirements of the construction, but not claimed as a feature of the invention.

Having described my invention, I claim:

1. In a display device, the combination of opposite bases spaced apart and joined one to the other and each supporting a vertical post, bars fixed in each of said posts and extending laterally of the posts on opposite sides thereof, said bars being spaced one from another vertically, a plurality of display racks supported on said bars one above another, each rack having a longitudinal medial partition extending above the sides of the rack, and a plurality of transverse partitions having their outer ends substantially flush with the upper edges of the sides of the rack and their inner ends substan-

tially flush with the upper edge of said medial partition, said transverse partitions being adjustable upwardly to open the racks longitudinally.

2. In a display device, the combination of opposite bases spaced apart and joined one to the other and each supporting a vertical post, transverse bars secured in said posts, a plurality of racks spaced apart vertically and supported on said bars in fixed relation to said posts, each lower rack being substantially longer and wider than the racks above it, and transversely arranged, partitions serving to divide each rack into opposite end bins and a plurality of side bins and adjustable to open one bin to another.

3. In a display device, the combination of a suitable frame support, a plurality of racks spaced apart vertically and supported on said frame, each lower rack being substantially longer and wider than the racks above it and each rack having a longitudinal medial partition and a plurality of adjustable transverse partitions, whereby upon adjustment of the transverse partitions the racks will be opened full length.

In testimony whereof, I affix my signature.

CARL J. FAULKNER.
